TRAVERSE MOTION MECHANISM OF DRUM
WINDERS

Kyugoro Sakamoto, Hamamatsu, Japan

Application October 24, 1938, Serial No. 236,737
In Japan June 18, 1938

2 Claims. (Cl. 242—43)

This invention relates to improvements in a traverse motion mechanism of drum winders for winding a strand on a bobbin.

In a known drum winder wherein a drum with a continuous helical groove of opposite directions for receiving and guiding a strand is employed, special construction and arrangement are required for the helical groove on the drum so as to cause the strand to traverse correctly over every crossing point of the groove having opposite directions.

The main object of this invention is to provide a rocking guide bar in front of the drum so that the entering direction of a strand automatically changes to and fro so as to conform to the direction of the helical groove on the drum by which the strand is guided.

In the drawing, Figure 1 is a side elevation of a drum winder provided with a traverse motion mechanism according to this invention.

Figure 2 is a front elevation of Figure 1.

Figure 3 is a part sectional plan view of the same.

In an ordinary drum winder of this kind, a strand is sent to the drum through a fixed guide point which is situated at a distance in front of the drum, and is directly received by a continuous spiral groove. For this reason, the entering direction of the strand relative to the axial line of the drum is reversed on each side of a line corresponding to the line C—C of Fig. 3 of the drawing connecting the fixed guide point and the longitudinal center of the drum, so that it coincides with the direction of the spiral groove on one side of the line, while it is in an opposite direction to that of the groove on the other side of the line. Therefore, when a strand is received and guided by the groove on one side of the above line where the direction of the groove is opposite to the entering direction of the strand, and the strand is being received at a point where the groove is intersecting, the strand is apt to get in the wrong groove the direction of which coincides with the entering direction of the strand.

In order to avoid this drawback, the grooves of opposite directions have been prepared in different constructions and/or arrangements at intersecting points so as to guide the strand in a correct groove, but the manufacture of such grooves on the drum is very difficult and expensive.

According to this invention, the entering direction of the strand always coincides with the direction of the groove so that a special construc-

tion or arrangement of the groove at intersecting points is not required.

In the drawing, 1 is the frame of the drum winder on which are mounted shafts 2 and 3. A drum 6 and a pinion 7 are fixed on the shaft 2 while a circular cam 9 and a tooth wheel 8 are fixed on the shaft 3, the pinion 7 and the wheel 8 being geared together.

A pair of levers 10 are pivoted on the frame at a spindle 5, and a spindle 11 for a bobbin is freely mounted on the levers 10. A crank lever 12—13—14 is loosely mounted on the frame through a hollow bracket 15, and a spring 16 acts to have a roller 17 provided at the extreme end of the upper arm 12 of the crank lever in contact with the circular cam 9.

A lever 20 is pivoted on a pin 21 fixed to the frame, and a metal bar 22 extending along the lever 20 is fixed to the lever at one end, the free end being bent in a right or acute angle so as to prevent a running strand from getting off the metallic bar. The lever 20 is linked at an end with the free end of the lower arm 14 of the crank lever, so that when the crank lever is rocked the lever 20 is also rocked.

The gear ratio of the toothed wheel 8 and the pinion 6 is determined by the number of pitches of the spiral groove, so that the circular cam 9 turns one revolution during the time that a strand returns to the same point being guided along the continuous groove. If, for example, the groove has three pitches in each direction, the gear ratio should be six.

The profile of the cam surface is such that about half a circumference is high and the other half is low, the parts intermediate of these two surfaces being sloped. Each sloped part should be limited to such a circumferential length that the roller 17 changes the position on the surfaces in a shorter time than that of the drum 6 rotates one revolution.

It is understood from the above explanations that the lever 20 is rocked around the pin 21, taking alternately the position A—A and B—B on Figure 2, and each oblique position is kept unaltered during the time when the drum is rotating three turns in this example.

The strand-receiving position at the groove on the drum should be so determined that within the time that the strand is being guided from the outermost intersecting point G to the end of the groove H and H to G, the lever 20 changes its position from A—A to B—B, and within the time that the strand is being guided from the other outermost intersecting point E to the end F and

F to E, the lever changes its position from B—B to A—A.

- In operation, a strand comes from a source, not shown, through a fixed guide 23 to the groove 5 on the drum, and is wound on the spindle 11. This spindle is rotated by friction caused at the contacting surface with the drum as illustrated on the attached drawing or may be driven independent of the drum. Before the strand is received by the groove, it passes under the metal bar 22, which, when the strand is received by the groove traveling from the point H to F, takes the oblique position A—A, and when the strand is received from the point F to H in the 10 return travel, the bar takes the position B—B, so that the travel of the strand-receiving point on the drum naturally causes the strand to travel along the bar in the direction as shown by arrows R.
- 20 When the strand-receiving point on the drum moves over the points G or E towards the end of the groove, the lever changes its position from A—A to B—B or B—B to A—A as above mentioned, so that the strand quickly advances along 25 the metallic bar toward its end, and returns to the opposite direction while the strand-receiving point on the drum is transferred to the groove of the opposite direction.

On account of this action, the entering angle 30 of the strand will always conform to the direction of the groove, so that the strand does not enter into the groove of the opposite direction when it is passing an intersecting point.

What I claim is:

- 35 1. A traverse motion mechanism for drum

winders for winding strand material, comprising a rotating drum with a continuous and crossed helical groove thereon for receiving and guiding a strand, a guide bar in front of said drum, said bar being adapted to assume two oblique positions opposite to each other relative to the axis of the drum and being arranged to guide the strand which is received by the helical groove on the drum, and means to quickly rock the guide bar to take the oblique positions alternately when the strand is changing its traversing direction on the drum and to keep the bar stationarily in the oblique position until the strand nearly traverses the whole length of the drum. 15

2. A traverse motion mechanism for drum winders for winding strand material, comprising a rotating drum with a continuous and cross helical groove thereon for receiving and guiding a strand, a guide bar in front of said drum, said bar being adapted to assume two oblique positions opposite to each other relative to the axis of the drum and being arranged to guide the strand which is received by the helical groove on the drum, a circular cam being rotatable in a definite relation with the drum so that the cam rotates one turn while the drum rotates a number of turns being twice the number of pitches of the helical groove in each direction, and a link member pivoted on the frame which transmits rocking motion from the cam to the guide bar so as to have the bar once take the oblique positions alternately in one turn of the cam. 20 25 30 35
